UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

PRESENTING APPARATUS.

Application filed November 4, 1920. Serial No. 421,681.

This invention relates to apparatus for presenting articles, as for example various kinds of shoe linings of felt or other material, in a convenient position before an operator. While illustrated as an apparatus for securing in shoes short pads of felt, known as "heel pads", the machine is adapted for presenting various articles, as for example any of the various other sizes of protective linings, such as "sock linings", and the term "linings" will be used in a broad sense as including heel pads. Moreover, certain features of the invention are well adapted for use in various types of delivery and other apparatus.

The invention is shown as embodied in a machine of the type illustrated in my co-pending application No. 242,763, filed July 1, 1918. In machines of this type the linings are contained in interchangeable magazines, from which they are extracted one at a time by a moving support bearing picker-mechanism; adhesive is applied to the lining on the support, and the support is then moved to hold the adhesive-coated lining in a convenient position before the operator. The operator forces the inside of the shoe against the adhesive-coated side of the lining, and the pressure of the shoe against the support is utilized to restore the picker-mechanism thereon to inactive position, thereby releasing the lining and resetting the pickers. This general method of operation being clearly shown in my earlier application, no extended discussion of its many advantages is here deemed necessary.

In placing linings in shoes, it is desirable that they be positioned therein with accuracy. An object of this invention is to provide gaging means for positioning a shoe with respect to the lining as it is presented by the support. Inasmuch as each of the several magazines contains linings of different size, it becomes necessary to adjust this gaging means each time a new magazine is brought to operative position. A further object of this invention is to provide a device for adjusting the gaging means for linings of different sizes and also to arrange one of these devices for each magazine in such manner that the changing of the magazines shall automatically change the gage-adjusting devices. As shown herein, the gage is mounted in the oscillating support, and con-

tacts with the inside of the counter portion 55 of the shoe. It is illustrated as being spring-pressed to outermost position, and the adjusting device is shown as a fixed abutment against which the gage is pressed to adjusted position by oscillation of the support. One of these fixed abutments is shown as mounted on each of the magazines, whereby changing the magazines automatically brings a new gage-adjusting device to operative position.

By this arrangement, no matter which magazine is in use, the gaging means is at all times so set that a shoe in the hands of an operator is accurately positioned with respect to the lining which is to be secured therein.

The proper operation of the adhesive-applying mechanism is most important in an apparatus of this character. If a magazine should become empty during the operation of the machine, or if for any other reason the picker-arm should fail to withdraw a lining from the magazine, this adhesive-applying mechanism would, if not prevented, discharge adhesive in the usual way, and this would quickly gum the picker-mechanism. An important object of my invention, therefore, is to provide means which will maintain inoperative the adhesive-applying mechanism in case the picker-arm fails to withdraw a lining from the magazine. In some of its aspects this combination of a work support, operating means, and a work-controlled safety device, presents broad novelty in that said device is suited for use with other operating means than an adhesive-applying apparatus, and for co-operation with supports for other articles than linings. Further objects of my invention are to secure an improved adhesive-applying mechanism, by providing means to circulate adhesive constantly from the bottom of the reservoir to the top, thereby avoiding the formation of a hard crust on the surface of the adhesive; to provide means for varying the pressure of the adhesive in the mechanism, thereby at the same time varying the quantity of adhesive applied to each lining; and to provide for adjusting the extent of downward movement of the adhesive-applying head.

Still other objects of my invention are the provision of a turret mounting for the magazines; improved means for smoothing the

pad on the support; novel mechanism for positively locking the picker-mechanism in case the presentation of a shoe by the operator fails to do so; new picker mechanism 5 acting to stretch a lining on the support; an improved laminated surface for the head of the support; and other improvements which will be apparent from the following detailed description; and which are more particularly pointed out in the appended claims.

While illustrated in an apparatus of the class described, my invention in certain of its aspects is capable of very general use. It is not the intention to limit its scope by 15 reason of the illustrative embodiment shown herein, but solely by the terms of the claims.

Referring now to the accompanying drawings:

Fig. 1 is a side elevation of the machine 20 with parts of the driving mechanism shown in section;

Fig. 2 is a front elevation of the machine broken away to show the drive shaft and associated mechanism in section;

Fig. 3 is a detail view of the gear pump 25 used in the pasting mechanism;

Figs. 4, 5, 6 and 7 are detail views of the oscillating support in various positions;

Fig. 8 is a view of the paste applying device and the safety mechanism for maintaining it in inoperative position;

Fig. 9 is a section taken longitudinally through the paste applying device;

Fig. 10 is a top plan view of the head of 35 the oscillating support;

Fig. 11 is a front elevation of the head of the oscillating support showing it in co-operative relation to the safety mechanism for the paste applying device;

Fig. 12 is a front elevation of the lower 40 part of a magazine;

Fig. 13 is a horizontal section through one of the magazines;

Fig. 14 is a section through one corner of 45 the head of the oscillating support, showing the manner of securing a rubber pad thereto;

Fig. 15 is a section on the line 15—15 in 50 Fig. 16 showing the adjustable connection between the paster-head lever and the bell-crank lever which operates it; and

Fig. 16 is a side elevation looking from the left in Fig. 15 showing the same adjustable connection.

The principal parts of the apparatus in 55 which my invention is embodied, are the magazines 27, containing heel pads or linings, a paste-applying mechanism 42, and an oscillating picker-arm or lining support 52. Upon tripping the starting treadle, suitable mechanism hereinafter described moves this support or picker-arm upwardly from the position shown in Fig. 4 to the position shown in Fig. 5. Here the picker-mechanism seizes the lowermost lining, and the

support is oscillated downwardly, under a lining-smoothing device 39, about 45 degrees, whereupon it stops momentarily under the paste-applying mechanism. The surface of the lining is coated with paste, 70 and the support then oscillates downwardly to its position of rest, shown in Fig. 7. In this position it presents the paste-coated lining in a convenient position before the operator, who presses a shoe against it, thereby securing the pad to the inside heel surface or heel seat of the shoe.

The machine is mounted upon a frame 20 and is driven by an electric motor 22 set in operation when desired by a switch 21. The motor drives, by means of a belt, as shown in Fig. 2, a main drive shaft 23. At 25 is shown a cam disk similar to the one illustrated in my previous application and containing various cam surfaces for actuating the mechanism of the machine. This cam disk is rotatably mounted on the shaft 23. As shown in Fig. 2 there is also rotatably mounted on shaft 23 a clutch disk 24 bearing two planetary gears 26 arranged with a large gear portion meshing with a gear surface on shaft 23 and a smaller gear portion meshing with a gear on the internal surface of cam disk 25.

When the current has been turned on at 21 the shaft 23 rotates constantly, thereby rotating planetary gears 26. If, now, the cam disk 25 is maintained stationary, the planetary gears 26 will ride on the internal gear on the cam disk and thereby rotate clutch disk 24. If, on the other hand, the clutch disk 24 is maintained stationary, the pivotal mountings of planetary gears 26 are also stationary and these gears, as they are revolved by shaft 23, drive cam disk 25 through the internal gear thereon. Thus, if either one of the two disks 24 or 25 is maintained stationary, the other disk is compelled to rotate at a reduced speed by the planetary gears which, in turn, are driven by shaft 23.

As shown in Fig. 1 the cam disk 25 is normally maintained in a stationary position by the locking of a curved lever 18 with a notch 17 in the surface of the cam disk. One end of the curved lever 18 is connected to a treadle 16, upon operation of which the end of the lever is withdrawn from notch 17 and maintained in that position by the surface of cam disk 25 until the cam disk has made one complete revolution, whereupon the lever again interlocks with the notch. At the time the lever 18 is withdrawn from notch 17 the opposite end of the lever is forced down on a spring which in turn clamps a brake shoe 19 against the clutch disk 24. It is evident therefore that when the treadle is operated the cam disk 25 is free to rotate while the clutch disk 24 is frictionally held until the

pivoted lever 18 again snaps into notch 17 after one rotation of the cam.

By this driving mechanism it is possible for the operator to arrest the operation of the machine at any time manually, and the machine itself is protected in case any of the mechanism should jam, since the stopping of the rotation of cam disk 25 from either of these causes would only result in 10 relative slipping of the brake shoe 19 and the clutch disk 24. In order to obviate possible slipping at any point in the cycle, as for example, when the oscillating support passes under the paste-applying mechanism,

15 I form a projection 77 on the surface of cam disk 25 upon which one end of lever 18 rides, which acts, at this point in the cycle of the machine, to force lever 18 downwardly, thereby applying greater pressure on 20 brake shoe 19 and holding clutch disk 24 more firmly. This arrangement applies a much greater power to cam disk 25 at this particular point and insures against stopping of the machine.

25 The driving mechanism above referred to constitutes no part of the present invention but is described and claimed in an application, Serial No. 129,468, filed August 16, 1926, which is a continuation in part of 30 this application.

In order to provide for a quick change from one size of linings to a different size, I mount a number of magazines 27 upon a rotatable turret 28. At 29 in Fig. 1 is 35 shown an upright support upon which the turret 28 is mounted. As shown at 30, on the lower surface of the rotatable turret there is a projection and on a fixed collar on support 29 there is a series of notches, 40 one notch for the positioning of each magazine in operative position. Upon the turret 28 there are also mounted a series of abutments 31, one for each magazine.

The magazines themselves, as shown in 45 Figs. 1, 2, 12 and 13, bear adjustable front plates 32 as shown in my prior application. The mounting of each individual magazine as shown at 33 is in the form of a U-shaped support which is seated on a horizontal pin on the rotatable turret and through which 50 project set screws for raising and lowering the magazine with relation to the support on the turret. I have arranged for varying the size of the magazine by means of a set of 55 adjustable guides. As shown in Figs. 1 and 13 these adjustable guides 34 are members which comprise vertical strips which contact with the edges of the linings, and legs at right angles thereto which slide 60 through apertures in the magazine and which may be clamped in any desired position of adjustment by set screws 35.

On the bottom of each magazine is 65 mounted a U-shaped abutment 38 shown in side elevation in Fig. 1 and in cross-section

in Fig. 5. Each of these abutments is secured to the magazine by screws which pass through slots in a flange thereon to provide for adjustment of the distance from the front edge of the magazine to the rear edge 70 of the abutment, according to the size of linings to be placed in the magazine. This abutment is for the purpose of adjusting a gage on the oscillating support as will hereinafter be described more fully. The 75 larger the linings are which are to be placed in the magazine, the further from the front edge of the magazine is the abutment adjusted.

A reciprocating magazine pusher 36 is 80 operated by a bell crank lever 37 from the cam disk 25. The cam disk is so shaped that when the oscillating support 52 reaches the position shown in Fig. 5 the magazine is lowered until it contacts with the abutment 85 31; after the withdrawal of the bottommost lining the magazine is pushed forward by the reciprocating pusher 36 and is given one or two sharp, short oscillations to jolt the remainder of the linings downwardly. 90

At 52 is shown an oscillating support or carrier arranged to be operated by connections from cam disk 25 by means of segmental racks 15. As shown in Figs. 4 to 7 inclusive this support is at rest when in 95 a convenient position to hold a lining for insertion in a shoe. From this position of rest it oscillates upwardly about 90° when the one revolution clutch is actuated, withdraws the bottommost lining from a magazine 27, oscillates downwardly about 45°, in which position it pauses momentarily while paste is applied to the surface of the lining, and then continues its downward oscillation to its position of rest. 100

Pivoted to a fixed arm on the frame of the machine, as shown in Figs. 1 and 2, is a smoothing lever or finger 39 one end of which is forked for the purpose of bearing on a lining on the head of the support or carrier 52 without contacting with the picker pins 62 on the support. The other end of the lever 39 is slotted to receive one end of an arm 40 which is mounted on a paste applying device 42. The paste applying device 42 is movable a short distance toward and from the arcuate path of the oscillating support 52 as hereinafter described and the arrangement is such that when the paste applying device is depressed the smoothing lever 39 will be raised and vice versa. The paste applying device is in raised position at the time the oscillating support withdraws a lining from the magazine and the lever 39 is at this time firmly pressed into position to contact with the head of the oscillating support at the beginning of the downward movement of the latter, to smooth the lining therein. 115

When the oscillating support stops momen- 120

125

130

tarily in its downward movement beneath the paste applying device in the position shown by full lines in Fig. 6, the paste applying device is lowered upon the head of the support by a lever 58 actuated from the cam disk 25. During the upward swinging movement of the support the paste applying device is momentarily depressed a sufficient amount to raise the smoothing finger to avoid interference with a member carried by the support as will hereinafter be explained.

The paste applying device 42 is mounted on one end of a lever 79, the other end 15 of which is pivotally mounted on the frame, as shown in dotted lines at 80 in Fig. 1. Levers 58 and 79 are secured together by an adjustable device shown in detail in Figs. 15 and 16. A cylindrical, eccentrically-bored sleeve 81 is secured by a bolt and nut 82 to a lug on the bottom portion of lever 79. This sleeve has a knurled head 83 by which it may readily be turned when the clamping nut and bolt 82 are loosened. 25 Mounted on the eccentric 81 is a square bearing block 84 sliding in a slot 85 in lever 58.

By this mounting, lever 79 may be adjusted vertically with reference to lever 58 by turning eccentric 81, thereby determining 30 the extent of the downward oscillation of lever 79, and the pressure acting against the device 42 carried thereby when it is in contact with a lining on the oscillating head.

Paste is supplied to the paste applying mechanism by a constantly operating gear pump shown at 44 in Figs. 2 and 3 and operated by means of bevel gears 43. This pump is mounted in the bottom of a paste reservoir 78 and acts constantly to force 35 paste into the tube leading to the paste applying device, and since the latter is operated intermittently the constantly operating pump maintains a considerable pressure therein. For the double purpose of determining the amount of this pressure and securing the circulation of paste from the bottom of the reservoir to the top, I provide 40 a bypass or overflow tube 45, shown in Fig. 2, in which is mounted a valve 46 which 45 can be operated to vary the effective cross section of the bypass 45.

As pointed out above it is desirable to prevent the actuation of the paste applying mechanism if the oscillating support fails 50 to withdraw a lining from the magazine. The mechanism for this purpose is shown in detail in Figs. 8 to 11 inclusive and in relation to the entire machine in Figs. 1 and 2. There is a reciprocating valve 47 in the 55 paster 42 normally closed under spring pressure and adapted to be opened by pressure on the head 48 of the valve stem. At 60 49 is shown a swinging pawl which in one position will act as a cam surface to force the head 48 of the valve 47 inwardly when

the paster 42 is lowered against it. When the paster is raised the head 48 swings pawl 49 about its pivot to inoperative position where it is locked by a trigger 50. A trip lever 51 (Fig. 1) is mounted on the fixed arm which supports the paste applying mechanism in such a way as to allow for a slight oscillation. This lever is arranged with a portion in the path of the head of the oscillating support and with an offset portion arranged beneath one end of trigger 50. In the surface of the head 53 of the oscillating support or carrier 52 there is a groove 59, shown in Figs. 10 and 11. If there is no lining on the support in its 75 downward movement the trip lever 51 drops into groove 59 by its own weight and thereby maintains the valve in the paste applying mechanism in its closed position. However if there is a lining 60 on the head 53, as shown in Fig. 11, it will bridge the groove 59 and act as a cam surface to raise the trip lever 51, thereby releasing a pawl 49 from trigger 50 and causing valve 47 to be opened 80 for the application of paste to the lining. 90

As shown in Fig. 14 the head 53 of the oscillating support 52 has a laminated surface pad shown at 54, 56 and 57. 54 is a piece of leather secured by tap screws 55 or otherwise to the metallic head 53. A 95 piece of canvas or other fabric 56 is glued to the surface of this leather and a piece of sponge rubber 57 is vulcanized to the canvas. By this construction I secure a rubber surface on the metallic head 53. 100

In general the picker mechanism for securing a lining on the head of the support is similar to the mechanism shown in my prior application. A spring pressed plunger 63 carries pins 62 at its forward end and 105 a pivoted pawl 70 intermediate its ends. A second spring pressed plunger 61 has mounted thereon a head 75 adapted to be pressed inwardly by a shoe in the hands of an operator as shown in Fig. 7. There is also fixedly mounted on plunger 61 a second head 76 for actuating the rear picker pins. These pins are mounted on a pivoted lever 72 under spring tension and in contact with the head 76. Thus the lever 72 is normally maintained in inoperative position by its spring and at a proper time in the cycle of the machine is pressed outwardly by the head 76. Because of the mounting and shape of lever 72, it moves in a path almost 110 tangent to a pad on the support, thereby maintaining tension on such pad between the front and rear picker pins, and securely fastens the pad to the support. A pivoted lever 64 is secured at one end to plunger 61 and fixedly mounted on the pivot of this lever is a small cam or recessed disk 66. The free end of the lever 64 is adapted to snap over the end of a trigger 65, as shown 115 in Fig. 4, for maintaining the plunger 61 120 125 130 135 140 145 150

in inactive position. It will be observed that when the plunger 61 is pressed inwardly by the pressure of a shoe against the head 75 the abutment 69 contacts with the pawl 70 to force plunger 63 into inactive position also. Should the pressure by the operator not be sufficient to lock the plungers in inactive position against the trigger 65, upon the upward oscillation of the support 10 the cam 66 will contact with a fixed abutment at 67 (Fig. 5) upon the frame of the machine, turning lever 64 and positively forcing the lever far enough to make sure that it will lock with trigger 65. To insure 15 against interference with the upward swinging movement of the support by engagement of the smoothing lever 39 with the head 75 in case the plungers 61 and 63 should not be locked in inactive position, 20 the smoothing lever is adapted to be momentarily raised to provide clearance between it and the head 75. This raising of the smoothing lever is effected by a slight depression of the paste applying device 25 which is timed to occur just after the support has swung past said device.

When the support oscillates upwardly a fixed abutment 71 on the frame of the machine contacts with one end of pawl 70 to 30 release plunger 63. This forces the pins 62 outwardly into position to seize the lowermost lining in a magazine and withdraw it therefrom as the support oscillates downwardly. After the lining has been smoothed 35 on the support by contact with the fork 39, the trigger 65 is released, as shown in Fig. 6, by a pivoted pawl 68 which yields on the upward movement but forms a fixed cam surface on the downward movement for tripping the trigger 65. The pad is thereafter maintained stretched in a smoothed position by the two sets of spring-pressed pins.

Mounted to reciprocate in the head of the support is a U-shaped gage 73 which is normally spring-pressed into its outermost position as shown in Fig. 10. On the upward movement of the support this gage contacts with the abutment 38 on the bottom of the magazine then in use and is pressed inwardly to adjusted position thereby. At this time in the cycle of the operation of the machine the plunger 63 is in its innermost position as shown in Fig. 4. Immediately after the gage is adjusted by the abutment 38 this 55 plunger 63 is released by the abutment 71 and a portion of the head of this plunger bearing a toothed surface 74 clamps down upon the two legs of the gage 73 to hold it in adjusted position. Thus the gage is released each time a shoe is placed against the head of the support and is reset each time a lining is withdrawn from the magazine in use.

As previously pointed out, the gage 73 is 60 so adjusted by the various abutments 38, that

when shoes of various sizes are placed over the head of support 52, with the counter-portion of each shoe resting on the gage, the front edge of the heel-pad will always be at the same point on the inner sole of the shoe.

Having described the machine in detail one cycle will be followed through to illustrate the operation of the machine.

At the beginning of the cycle the oscillating support 52 is in the position shown in Figs. 1 and 4 with both sets of picker pins locked in inactive position. The operator touches the treadle 16 with his foot thereby tripping the one revolution clutch, and the support oscillates upwardly through an angle of about 90°. At the end of this upward oscillation the spring pressed gage 73 is set by the abutment 38 on the selected magazine while at the same time the fixed abutment 67 on the frame of the machine 75 forcibly withdraws the plungers 61 and 63 to their locked position in case the operator may have failed to do this during the preceding cycle. Immediately thereafter the 80 fixed abutment 71 trips the pawl 70 and the plunger 63 reciprocates upwardly forcing the pin 62 into the material of the lowermost lining in the magazine, and holding the gage 73 in adjusted position. Thereupon the support begins its downward oscillation, the lining is smoothed out by the fork 39 and grasped by the pins on the lever 72 to stretch it in this smoothed condition, and the support then stops momentarily underneath the paste applying mechanism. The paster descends, the valve therein is opened, and the pressure in the paste applying mechanism forces a small amount of paste outwardly upon the lining. The paster then rises and the support oscillates downwardly to the position shown in Fig. 7. The operator manually places the shoe against the head of the support, being guided by the contact of the gage 73 with the inside of the counter portion of the shoe. As the shoe is placed against the support the head 75 is pushed inwardly to withdraw plungers 61 and 63 to a position where they are locked by trigger 65 in the position of 90 rest shown in Figs. 1 and 4, releasing the hold of the picker pins on the pad, and leaving it adhesively secured in position in the shoe.

While I have shown the various features 120 of my invention as embodied in an apparatus which I have described with great particularity, it is to be understood that they may be used in machines and apparatus of various types, and in various specific forms of construction. It is to be understood that the described embodiment is illustrative only, and that the scope of the invention is not to be limited thereby, but only by the appended claims.

Having described my invention, what I claim as new and desire to secure by Letters Patent of the United States is:

1. In a presenting apparatus, a magazine for objects to be presented, a member movable to extract an object therefrom, an adjustable gage on said movable member, and means on said magazine for adjusting said gage.
10. 2. In a presenting apparatus, a magazine for objects to be presented, a member movable to extract an object therefrom, a movable gage on said member, and a device on said magazine to move said gage to a predetermined adjusted position with relation to the object extracted from the magazine.
20. 3. In a presenting apparatus, a movable support for an article, a gage thereon for properly positioning a second article in one position of said support in co-operative relation to said first article, and means for adjusting said gage in another position of said support.
25. 4. In a presenting apparatus, a movable support for a lining, a gage thereon for positioning a shoe in proper relation thereto in one position of said support, and a device for adjusting said gage in another position of said support.
30. 5. In a presenting apparatus, a movable support, and a gage thereon for positioning an article, in combination with a fixed abutment in the path of said gage to contact with said gage to adjust it.
35. 6. In a presenting apparatus, delivery mechanism for articles including a gage, and means for automatically adjusting said gage according to the size of article delivered thereby.
40. 7. In a presenting apparatus, a magazine for articles, a movable support for delivering articles therefrom, a spring-pressed gage on said support, and an abutment on said magazine for adjusting said gage.
45. 8. In a presenting apparatus, a magazine for containing articles, a movable support for delivering articles therefrom, a spring-pressed gage on said support, and means on said support to maintain said gage in adjusted position.
50. 9. In an apparatus for presenting articles in a desired position, a plurality of magazines for various sizes of articles, a movable support for delivering articles therefrom, an adjustable gage on said support, and a device on each magazine whose position corresponds to the size of articles intended to be placed therein for adjusting said gage.
55. 10. In a presenting apparatus, a plurality of magazines for articles of different sizes, a support therefor movably mounted in order that each magazine may be placed in an operative position, a movable member for delivering articles from the magazine, a gage on said member adapted to be adjusted
60. in different operative positions, and a device mounted on each magazine at a predetermined distance from an edge of an article therein for adjusting said gage.
65. 11. In a presenting apparatus, a plurality of magazines for articles of different sizes, a support therefor movably mounted in order that each magazine may be placed in an operative position, a movable member for delivering articles from the magazine, a gage on said member adapted to be adjusted in different operative positions, and a device removably mounted on each magazine and adjusted at a predetermined distance from an edge of an article therein for adjusting said gage.
70. 12. In an apparatus for applying linings to shoes, a plurality of interchangeable magazines for various sizes of linings, a rotatable turret on which said magazines are mounted, a movable support for delivering articles from the magazine, a gage on said support adapted to be adjusted in different operative positions, and a device on each magazine whose position corresponds to the size of linings intended to be placed therein for adjusting said gage.
75. 13. In a presenting apparatus, a magazine for articles, a movable support for delivering articles from the magazine, and an adjustable gage on said support for positioning an article, in combination with means rendered operative by movement of said support for setting said gage in operative position.
80. 14. In a presenting apparatus, a magazine for articles, members adjustable to vary the size of said magazine, means for removing an article from the magazine and determining its position relatively to a second article subsequently assembled therewith, and an abutment on the magazine adjustable according to the particular size of articles therein for co-operating with said means to vary the relation of said first and second articles.
85. 15. In a presenting apparatus, a magazine for articles, said magazine bearing an abutment whose position corresponds to the size of articles therein, means for removing an article from the magazine, and a device adapted to be set by said abutment to determine the position of a second article relatively to the first.
90. 16. In a presenting apparatus, a magazine for a stack of linings, a member movable toward and from the magazine for removing linings therefrom, a gage for positioning an article relatively to a lining carried by said member, and a device mounted on said magazine at a predetermined distance from an edge of said stack of linings therein for positioning said gage.
95. 17. In a presenting apparatus, a magazine, a device for removing an article from

the magazine and presenting it in a desired position, a gage on said device for positioning a second article in co-operative relation to the first article at the place of presentation thereof, and means for adjusting the gage.

18. In a presenting apparatus, a picker device for transferring a lining from one locality to another, and a gage on the picker device for positioning a shoe in relation to a lining on said device, said gage being adjustable to vary the location of the lining longitudinally of the shoe.

19. In a presenting apparatus, in combination, a lining-supporting pad shaped to conform to the heel-seat portion of a shoe, means for supporting the pad rigidly in position for a shoe to be pressed against, and a gage to contact with the counter portion of the shoe to position the shoe relatively to the lining.

20. In a presenting apparatus, a device for seizing an article and transferring it from one position to another, and an adjustable gage mounted therein and adapted to position a second article relatively to the first without engaging the first article.

21. In a presenting apparatus, a support for an article, means including a movable member for fixedly securing an article to said support, and an adjustable gage, said gage being held in adjusted position by said movable member.

22. In a presenting apparatus, a movable device for seizing an article and transferring it from one position to another, means for fixedly securing the article to said device, an adjustable gage mounted therein for positioning a second article relatively to the first upon said device, and means for adjusting said gage.

23. A support for an article, comprising a movable head, an abutment in the line of movement of the head, and a spring-pressed, 45 U-shaped gage mounted in said head and adjustable to operative position against the influence of said spring by said abutment.

24. A support for an article, comprising a head, a gage adjustable toward and from said head, a spring urging the gage toward the limit of its movement in one direction, and means to clamp said gage in any desired position against the action of said spring.

25. A support for an article, comprising a head, a gage adjustable toward and from said head, a spring urging the gage toward the limit of its movement in one direction, means to clamp said gage in any desired position against the action of said spring, and means to release said clamp.

26. A support for an article comprising an article-holding member mounted to reciprocate therein, a gage mounted to reciprocate at right angles thereto, and a spring

acting to press said gage into a maximum position, said gage and said article holding member being arranged to contact with one another, whereby said member may hold said gage in any desired position, against the tension of said spring.

27. A support for an article comprising an article-holding member mounted to reciprocate therein, a gage mounted to reciprocate at right angles thereto, and a spring 75 acting to press said gage into a maximum position, said gage and said article-holding member being arranged to contact with one another, whereby said member may hold said gage in any desired position, against the tension of said spring, said article-holding member being so arranged that pressure directed against the support will withdraw said member and release the gage.

28. A movable support for an article, a gage movable in said support, a fixed abutment in the path of said support to effect relative movement of the gage and support, and a device to maintain said gage and support in the desired relative adjustment.

29. In an apparatus for applying linings to shoes, a support for a lining, a U-shaped gage having legs movable in said support, and a connecting part for engaging the counter portion of a shoe, means automatically to move said gage to a desired position, means for clamping the legs of said gage to maintain said gage in the desired position, and means to release said gage from said clamping means.

30. In a presenting apparatus, a magazine, a movable device for feeding articles therefrom, a gage movable in said device, means automatically to move said gage to a desired position, and means to maintain said gage in the desired position, said means being constructed and arranged to release said gage when pressure is directed against said device.

31. In a presenting apparatus, a magazine, a movable device for feeding articles therefrom, a gage movable in said device, means automatically to move said gage to a desired position, means to maintain said gage in the desired position, and mechanism operative when engaged by a second article superposed upon the first to release said gage from said last-mentioned means.

32. In a presenting apparatus, a magazine, a movable support to feed articles therefrom, a spring-pressed reciprocating article-seizing plunger mounted therein, means to hold said plunger in inoperative position, a gage spring-pressed to an outermost position and mounted in said support, an abutment on said magazine to press said gage to adjusted position, and another abutment thereafter operative to release said plunger from said holding means, said plunger and said gage being constructed with interengaging sur-

faces, whereby said plunger will clamp said gage in adjusted position.

33. In a presenting apparatus, a magazine, a movable support to feed articles therefrom, means to apply adhesive to an article fed by said support, a gage for positioning a second article with relation to the adhesive-coated article, and a device to set said gage according to the size of the adhesive-coated article.

34. In a presenting apparatus, a magazine, a movable support to feed articles therefrom, means to apply adhesive to an article fed by said support, a gage for positioning a second article with relation to the adhesive-coated article, and a device to set said gage according to the size of the adhesive-coated article, in combination with safety mechanism arranged to maintain inoperative the adhesive-applying means if there is no article on the movable support.

35. In a machine for securing linings in shoes, an oscillatory lining support having a groove in the supporting face thereof, means for moving the support first to a position of rest to enable the lining to receive a coating of paste and then to a second position where the lining is to be applied to a shoe, a pivoted lever riding idly in said groove if there is no lining upon the support and lifted by the lining if one is present upon the support, an adhesive-applying head, a valve in said head, a normally inoperative device for opening the valve, and means actuated by said lever when the latter is raised for rendering the valve opening device operative.

36. In a presenting apparatus, a support for a lining, means for moving said support to present the lining first in position to receive paste and second in position for application to a shoe, a device to apply paste to a lining on said support when the latter is in said first position, and means to prevent the application of paste if there is no lining on said support.

37. In a presenting apparatus, a support for a lining, means for moving said support to present the lining first in position to receive paste and second in position for application to a shoe, a device to apply paste to a lining on said support, when the latter is in said first position, means to feed paste to said device, and means to prevent the feeding of paste to said device if there is no lining on said support.

38. In a presenting apparatus, a movable support for an article, means for moving the support to a position of rest and there supporting the article in paste-receiving position, a device normally inoperative to apply paste to an article thus supported, means to render said device operative to apply paste to the article, said support being constructed and arranged to operate said means when

there is an article on the support and not to operate said means if there is no article on the support.

39. In a machine for applying adhesive to articles, a movable support for an article, means for moving the support to a position of rest and there supporting the article in paste-receiving position, a device normally inoperative to apply adhesive to an article on said support, and means to render said device operative when there is an article on said support.

40. In a machine for applying adhesive to articles, a movable support for an article, means for moving the support to a position of rest and there supporting the article in paste-receiving position, a device normally inoperative to apply adhesive to an article on said support, means to render said device operative, and mechanism to maintain said means in an inactive position if there is no article on the support.

41. In a machine for applying adhesive to articles, a movable support for an article, means for moving the support to a position of rest and there supporting the article in paste-receiving position, a device normally inoperative to apply adhesive to an article on said support, means to render said device operative, and mechanism arranged to actuate said means if there is an article on said support and to remain idle if there is no article on said support.

42. In a machine for applying adhesive to articles, a movable grooved support for an article, a device to apply adhesive to an article on said support, means including a normally closed valve for supplying adhesive to said device, means for opening said valve, and a trip lever arranged to ride idly in the groove if there is no article on the support, and to be moved by contact with an article on said support to actuate said last named means.

43. In a machine for applying adhesive to articles, a movable support for an article, a device normally inoperative to apply adhesive to an article on said support, a moving pawl arranged in active position to render said device operative, and to remain idle in another position, a latch for holding said pawl in idle position, and means for releasing said latch to enable said pawl to be moved from idle to active position if there is an article on the support.

44. In a device for applying adhesive to articles, a movable support having a groove in the supporting surface thereof, a pivoted lever riding idly in said groove if there is no article on the support and lifted if there is an article thereon bridging the groove, an adhesive-applying head, a valve in said head, a swinging abutment arranged in one position to open said valve, a trigger-lock arranged to hold said abutment in an inactive

- position, and arranged to be released by said pivoted lever when it is raised.
45. In a presenting apparatus, means for supporting an article and moving it into position for presentation, a device for applying adhesive to an article being moved by said means, mechanism to vary the amount of adhesive applied by said device and means to prevent the application of adhesive if there is no article on the supporting means.
46. In a presenting apparatus, means for supporting an article and moving it into position for presentation, a device for applying adhesive to an article being moved by said means, means for feeding adhesive to said applying means, and mechanism to vary the amount of adhesive thus fed.
47. In a machine for securing linings in shoes, a magazine for holding a plurality of linings, means for feeding linings from the magazine, a device for applying adhesive to a lining being fed, a conduit for feeding adhesive to said device, and means for varying the pressure of the adhesive in said conduit.
48. In a machine for securing linings in shoes, a magazine for holding a plurality of linings, means for feeding linings from the magazine, a device for applying adhesive to a lining being fed, mechanism for feeding adhesive to the lining, and means for varying the amount of adhesive applied to each lining.
49. In a machine for securing linings in shoes, an adhesive-applying member, means for supporting a lining and moving it toward and from said member, mechanism comprising a valve arranged when open to supply adhesive to said member, means acting continuously to force adhesive into said feeding mechanism, a device with an opening adapted to permit the overflow of adhesive when said valve is closed, and means adjustable to vary the size of the opening in said device, thereby to vary the pressure of the adhesive in said feeding mechanism.
50. In a presenting apparatus, means for supporting an article and moving it into position for presentation, a reservoir, means intermittently operable for applying liquid to an article being moved by said means, mechanism acting constantly to supply liquid from the reservoir to said liquid-applying means, and an over-flow device for returning surplus liquid to the reservoir.
51. In a presenting apparatus, means for supporting an article and moving it into position for presentation, a reservoir, means intermittently operable for applying liquid to an article being moved by said means, mechanism to supply liquid from the reservoir to said liquid-applying means, an over-flow device for returning excess liquid to the reservoir, and means for varying the effective cross-section of said overflow device.
52. In a presenting apparatus, means for supporting an article and moving it into position for presentation, means intermittently operable for applying liquid to an article being moved by said means, mechanism acting constantly to supply liquid thereto, and a device permitting the escape of excess liquid.
53. In a presenting apparatus, means for supporting an article and moving it into position for presentation, a reservoir, means intermittently operable for applying liquid to an article being moved by said means, mechanism acting constantly to supply liquid thereto from the reservoir, and an overflow device for returning excess liquid to the reservoir above the level of the liquid therein.
54. In a presenting apparatus, means for supporting an article and moving it into position for presentation, mechanism to apply liquid to an article being moved by said means, driving means for said mechanism, and means to vary the power transmitted by said driving means.
55. In an apparatus for applying linings to shoes, a movable support for a lining, a mechanism for applying adhesive to a lining on said support, means including a friction device for moving said support past said mechanism, and means for increasing the friction between the parts of said device as the support is moved past the paste-applying mechanism.
56. In a presenting apparatus, an oscillatory support for an article, means for oscillating said support, a device to smooth an article on the support as the latter is oscillated, and means to withdraw said device.
57. In a presenting apparatus, a magazine for blanks of sheet material, a picker head having a smooth surface for supporting a blank throughout the entire area of the blank, means for moving the picker head to feed a blank from the magazine to a position of presentation, means for applying adhesive to the blank while being thus fed, and a device for smoothing the blank against the blank supporting surface of the picker head before the adhesive is applied to the blank.
58. In a presenting apparatus, a movable support for a lining, a device against which said support bears during movement in one direction for smoothing the lining on the support, an adhesive applying device movable into and out of position to engage the lining, and means operative upon movement of the adhesive applying device toward the path of the support for withdrawing said smoothing device from said path.
59. In a presenting apparatus, an oscillatory support for a flexible article, a device against which said support bears before the movement of the support in the opposite

- direction for smoothing said article, and means for separating said device and the path of the support before the movement of the latter in the opposite direction.
- 5 60. In a presenting apparatus, a movable support for an article, pickers arranged independently to seize an article to hold it in place on the support, and a device slotted to avoid said pickers and arranged to bear 10 upon an article on said support to press the article against the support.
61. In a presenting apparatus, an oscillating support for an article, a reciprocating device for applying adhesive to an article on 15 said support, a pivoted lever arranged when in operative position to smooth the article on said support, and an abutment on said reciprocating device to force said lever into operative position.
- 20 62. A lining applying element comprising a picker arm provided with a metal head, a sheet of leather attached to the head, a sheet of fabric glued to the leather, and a sheet of rubber vulcanized to the fabric.
- 25 63. In a presenting apparatus, a movable member for supporting and transferring a flexible article, releasable means on said member for cooperating therewith to hold the article in place thereon, means thereafter 30 to engage another portion of the article and stretch it against the engaging means, and means for releasing said first-mentioned means.
- 35 64. In a presenting apparatus, a support for a flexible article, means for securing one portion of an article thereto, a device to smooth the article thereon, and means carried by said support to seize another portion of the smoothed article and stretch it against the securing means.
- 40 65. In a presenting apparatus, a support for a fabric, means for securing one portion of a fabric thereto, a slotted device to smooth a fabric thereon, and means comprising 45 picker pins adapted to penetrate said fabric below the slots while held by said device in smoothed condition, said pin-carrying means being arranged to apply tension to said fabric to maintain it in smooth condition.
- 50 66. In a movable support of the class described, a pivoted lever bearing means for holding an article on said support, a device 55 constantly acting to hold said lever in inoperative position, normally restrained mechanism constantly tending to oppose the action of said device, and means rendered operative by movement of said support for releasing said mechanism to force said lever into operative position against the opposition of said constantly acting device.
- 60 67. In a presenting apparatus, a picker head having a smooth surface for engaging a blank of sheet material, a reciprocatory picker pin adapted to be projected through 65 said surface, and an oscillatory picker pin adapted to be projected through said surface in spaced relation to the first pin.
68. In a presenting apparatus, a picker head having a smooth surface for engaging a blank of sheet material, a reciprocatory picker pin adapted to be projected through said surface, and an oscillatory picker pin adapted to be projected through said surface in spaced relation to the first pin, in combination with means for operating said pickers successively.
- 70 69. In a presenting apparatus, a member comprising a movable head, a picker movable in and out of the head, rotary means for withdrawing said picker, in combination with a device for operating said rotary means, and mechanism including a fixed abutment rendered effective by movement of said member for moving the picker 75 out of the head.
- 75 70. In an apparatus for presenting blanks of sheet material, a frame, a movable member comprising a head formed with a blank supporting face having a marginal contour corresponding to the outline of the blanks, a reciprocable picker normally projecting beyond said device, and rotary means for withdrawing said picker, in combination with a device mounted on said frame for 80 operating said rotary means.
- 85 71. In a presenting apparatus, a stationary frame, a movable head, a picker movable in and out of the head, a spring tending to force the picker outwardly, means including a rotary member for compressing the spring and retracting the picker, a latch for holding the picker retracted, and stationary means constructed and arranged to operate the rotary member and trip the latch upon 90 movement of the head.
- 95 72. In a presenting apparatus, a movable arm comprising a head, a picker movable relatively to said head, a lever fixedly mounted on a pivot for operating said movable picker, a recessed disk on one end of said pivot, in combination with a fixed abutment constructed and arranged to contact with the recess in said disk upon movement of the arm, to operate the lever for 100 movement of the picker.
- 105 73. In a presenting apparatus, a member comprising a movable gage, a device for holding said gage in a desired position, mechanism mounted on said member for retracting said device from gage-holding position, and means for operating said mechanism.
- 110 74. In a presenting apparatus, a movable support, a reciprocating gage for co-operation therewith, a device to secure said gage in a desired position, and means actuated by the movement of the support to release said gage from said securing device.
- 115 75. In a presenting apparatus, a mov-

able support, a reciprocating gage for co-operation therewith, a clamp on said support to hold said gage in a desired position, and an abutment which releases said

5 clamp when moved thereagainst by the movement of the support.

76. In an apparatus of the class described, mechanism for successively delivering articles therefrom, a plurality of magazines, a support therefor mounted rotatably in order that the various magazines may be used in co-operative relation to the delivery mechanism, and means for jolting the magazine in use between successive operations of the

15 delivery mechanism.

77. In a presenting apparatus, a magazine for holding a stack of articles, comprising a plurality of flat strips disposed in parallel relation and arranged to engage 20 and aline the edges of the articles, a pair of parallel supporting legs extending from the outer faces of each of said strips at right angles to said faces, and a frame for supporting the magazine having openings 25 therein for receiving said legs.

78. In a presenting apparatus, a magazine for holding a stack of superposed linings comprising a support for the bottom of the stack, a front plate spaced from the bottom 30 support to provide an outlet for the linings, guide members for the edges of the linings at the sides and rear of the stack, and means for supporting said guide members constructed and arranged to permit independent inward and outward adjustment 35 thereof.

79. In a presenting apparatus, a magazine for a stack of linings, said magazine comprising a hollow frame having openings 40 in the sides thereof, guide members for the edges of the linings having parallel supporting legs arranged for adjustment in the direction of their length in said openings, and means for securing the legs of 45 said guide members in adjusted position.

80. In an apparatus of the class described, a plurality of magazines, a support therefor mounted rotatably in such a manner that any desired magazine may be used, means 50 for pivotally mounting the magazines upon the support, feeding mechanism, and means for imparting a sudden oscillation to the selected magazine after each operation of the feeding mechanism.

81. In a presenting apparatus, a support 55 for presenting an article in a convenient position, a device movable to deposit adhesive on the article on said support, an actuating lever for said device, and means for varying the effective length of said lever to vary the extent of movement of said device.

82. In a presenting apparatus, a support 60 for presenting an article in a convenient position, a device movable to deposit adhesive on the article on said support, an actuating lever for said device, and means for varying the effective length of said lever to vary the extent of movement of said device.

adhesive on the article on said support, a moving lever to actuate said device, and means for varying the extent of movement imparted by said lever to said device.

83. An assembling machine for use in 70 making shoes comprising, in combination, a movable support for a part of a shoe, normally idle means for applying a coating of an adhesive to a part carried thereby, mechanism intermittently to move said support to and from position with respect to said means, and a controller actuated by engagement with the part on the support and effective during the motion of the support to said means to render said means 75 operative, the means being arranged to remain inoperative unless said controller is actuated.

84. An assembling machine for use in 80 making shoes comprising, in combination, a magazine for shoe parts, gaging and feeding means to deliver parts therefrom and present them for assembling, said means including an intermittently-movable support for said parts, normally idle means to operate on parts on the support during the pauses in its movement, and a controller operated by engagement with work on the support to render said means effective.

85. An assembling machine for use in 85 making shoes comprising, in combination, a source of supply of shoe parts, means including a movable support for delivering parts therefrom and presenting them in position for assembling, means for operating on a part on the support, and a connection actuated by the presence of work on the support to render said operating means effective, said operating means being arranged to remain idle unless said connection 90 is actuated.

86. An assembling machine for use in 95 making shoes comprising, in combination, a source of supply of shoe parts, means including a movable support for delivering parts therefrom and presenting them for assembling, means for operating on a part on the support, and a connection to control said operating means, said connection being constructed and arranged to co-operate 100 with the support to be actuated if there is a shoe part on the support and otherwise to remain idle.

87. An assembling machine for use in 105 making shoes comprising, in combination, an intermittently-movable carrier for a part of a shoe, normally-idle means arranged for movement in synchronism with the motion of said carrier to operate on a shoe part carried thereby, and connections including 110 a member arranged to be moved by engagement with a shoe part on the carrier to render said means operative and to remain idle if there is no part on the carrier to be engaged thereby.

88. In a presenting apparatus, a movable support for a lining, a device against which the support bears during movement in one direction for smoothing a lining thereon, an adhesive applying device movable toward and from the path of the support, and means operative upon movement of the ad-

hesive applying means away from said path for moving said smoothing device into operative position.

10

In testimony whereof I have signed my name to this specification.

FREDERICK M. FURBER.

CERTIFICATE OF CORRECTION.

Patent No. 1,604,161.

Granted October 26, 1926, to

FREDERICK M. FURBER.

It is hereby certified that error appears in the printed specification of the above numbered patent requiring correction as follows: Page 1, line 74, for the misspelled word "sliould" read "should"; page 2, line 127, strike out the article "the"; page 3, line 129, for the word "therein" read "thereon"; page 4, line 88, strike out the article "a"; page 9, claim 59, lines 129 and 130, strike out the words "before the movement of the support in the opposite" and insert instead "during its movement in one", and page 10, line 4, same claim, for the word "latter" read "support"; and that the said Letters Patent should be read with these corrections therein that the same may conform to the record of the case in the Patent Office.

Signed and sealed this 12th day of July, A. D. 1927.

Seal.

M. J. Moore,
Acting Commissioner of Patents.
